(57) **CLAIM**

The ornamental design for a bike light, as shown and described.

DESCRIPTION

FIG. 1 is a side perspective view of my new bike light;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken line showing in the drawings of the rear surface, the clip, and the single broken line that runs around the perimeter of the bike light is for the purpose of illustrating portions of the bike light and forms no part of the claimed design.
